United States Patent Office

Des. 179,474
Patented Jan. 1, 1957

179,474

INSTRUMENT PANEL

Mark E. De Groff, Tulsa, Okla.

Application May 5, 1955, Serial No. 35,853

Term of patent 14 years

(Cl. D26—1)

Fig. 1

Fig. 2

Figure 1 is a front elevational view of a panel showing my new design, and Figure 2 is a top view of the panel shown in Fig. 1.

I claim:

The ornamental design for an instrument panel, as shown.
